UNITED STATES PATENT OFFICE

2,458,028

OPERATING MECHANISM FOR
MACHINE GUNS

Francis I. Rataiczak, Dayton, Ohio, assignor to
General Motors Corporation, Dayton, Ohio, a
corporation of Delaware

Original application May 19, 1944, Serial No.
536,229. Divided and this application November
23, 1945, Serial No. 630,199

4 Claims. (Cl. 89—1)

1

This invention relates to ordnance and more particularly to an improved machine gun construction.

This application is a division of my application S. N. 536,229 filed May 19, 1944.

One object of this invention is to provide a low cost machine gun capable of firing high powered 60-caliber ammunition.

Another object of this invention is to improve upon the receiver construction so as to make a strong lightweight receiver suitable for mass production.

Another object of this invention is to provide a gun in which the parts are adapted to mass production and in which the parts of one gun are readily interchangeable with the parts of other guns.

A further object of this invention is to provide an improved mechanism for hand cocking the gun.

More particularly it is an object of this invention to provide a means for hand cocking the gun which makes it possible to hold the bolt in any desired position.

Further objects and advantages of the present invention will be apparent from the following description, reference being had to the accompanying drawings, wherein a preferred form of the present invention is clearly shown.

In the drawings:

Fig. 1 is a side elevational view of a gun embodying my invention;

Fig. 2 is a side elevational view similar to Fig. 1 but showing the breech cover raised;

Fig. 3 is a top view of the gun;

Fig. 4 is a fragmentary sectional view on an enlarged scale showing the rear portion of the gun;

Fig. 5 supplements Fig. 4 and shows the construction of the front portion of the gun;

Fig. 6 is a top view of the rear portion of the bolt;

Fig. 7 is a side view of the bolt portion shown in Fig. 6;

Fig. 8 is a top view of the bolt head showing one of the side rollers in section;

Fig. 9 is a side view of the bolt head shown in Fig. 8;

Fig. 10 is an elevational view of the bolt head cam; and

Fig. 11 is a vertical sectional view which shows the relationship of the shell feeding mechanism to the cover and the cam tube.

Referring now to Figs. 1, 2 and 3 of the drawing, reference numerals 50 and 52 designate the

2

breech housing or receiver and barrel respectively of a 60-caliber rapid fire machine gun. Reference numeral 54 designates generally the cover for the breech housing which is pivotally secured to the breech housing at 56. A belt feed mechanism 58 is removably secured to the cover member 54 in a manner to be explained more fully hereinafter. The feedway 60 which is secured to the breech housing 50 cooperates with the belt feed mechanism 58 to direct the feed belt and the cartridges carried thereby into the breech housing 50.

Reference numeral 64 designates generally an adapter which is used for mounting the gun and which incorporates a standard buffer arrangement, the details of which form no part of my invention and will not be described in detail. The cover 54 may be latched in its downward position by the cover latch 66 (Fig. 4) which engages the cover latch strike 68 carried by the breech housing 50. The latch 66 is operated by means of the handle 70 (Figs. 1, 2 and 3) which is arranged as shown. The latch 66 is normally held in latching engagement by the spring 72. Inasmuch as the details of the latch form no part of this invention, further description of the latch mechanism is believed to be unnecessary.

The breech housing 50 is made up in a novel manner in that it comprises stamped sheet metal elements to which the rear end piece 136 is attached. The rear end of the barrel 52 is provided with suitable interlocking locks 80 which lock the barrel in fixed relationship to the breech ring 82. The breech ring 82 is provided with a projecting key portion 96 at its lower front end which slides within a keyway 98 provided in the barrel extension 84 whereby the breech ring is allowed to reciprocate within the barrel extension but is not permitted to rotate relative the barrel extension. The barrel extension 84 is provided with a locking stud 108 which engages a slot 110 provided in the front end of the receiver 50.

The relatively heavy end piece 136 serves to reinforce the lighter weight stampings at the end thereof and also provides a rigid mounting member which may be machined the same as if the entire breech housing were made from a large piece of heavy bar stock.

The breech housing serves to guide the bolt assembly generally designated by the reference numeral 150. The rear end piece 136 is suitably machined so as to serve as the housing for the bolt buffer mechanism generally designated by the reference numeral 152 and best shown in Fig. 4. Since the bolt buffer mechanism which com-

prises a plurality of concentric springs is of standard construction and since the details thereof form no part of this invention, other than the manner in which the element 136 is formed and held in place, the bolt buffer mechanism will not be described in greater detail. The bolt assembly comprises a main bolt body portion 154 and a bolt head portion 156 which includes a shank 158 which telescopes into the bolt head cam element 166 carried within the recess 160 provided in the forward portion of the main bolt body 154.

A firing pin 170 is carried by the main bolt body 154 as shown and projects through a central aperture 172 provided in the bolt head 156. The lower side of the bolt head 156 is recessed as best shown in Fig. 4, for the reception of the shell extracting element 174 which is mounted on the pivot 176 and which is biased into shell engaging position by a compression spring 178. A shell ejector 180 is pivotally supported by the bolt head 156 and serves the usual purpose of a shell ejector.

The bolt head 156 is mounted for partial rotation relative to the main body portion 154 as will be explained more fully hereinafter. As best shown in Fig. 8, the bolt head 156 is provided with interrupted screw segments 182 which are adapted to interlock with complementary interrupted screw segments 184 provided within the breech ring 82 upon approximately a quarter turn of the bolt head. The bolt assembly 150 may be held in the rear position by the sear 186 which is normally biased into bolt latching position by the compression spring 188 arranged as shown in Fig. 4. Upon release of the bolt assembly by the sear 186, the bolt assembly moves forward until the bolt head rollers close against the cam surfaces 193 of the breech ring 82 at which time the bolt head stops and the rear portion of the bolt continues to move forward. The rollers 191 of the bolt head strike the cam surfaces 193 on the breech ring 82 so as to initiate rotation of the bolt head 156 just before the bolt head reaches its forward position. The continued forward movement of the rear portion of the bolt causes the cam surfaces 190 thereon to engage the projecting rollers 191 of the bolt head 156 so as to further rotate the bolt head. Rotation of the bolt head causes the interrupted screw segments 182 to interlock with the complementary interrupted screw sections 184 provided within the breech ring 82 so as to firmly hold the bolt head in shell firing position during the firing of the shell in accordance with well-known practice. After the bolt head has been properly locked in shell firing position, the firing pin 170 is carried forward relative to the bolt head into shell firing position. Firing of the shell causes recoil of the barrel together with the breech ring and the bolt assembly. Soon after recoil begins, the rollers 191 carried by the projecting shanks 192 of the bolt head will engage the cam unlocking surfaces 200 provided on the element 102 so as to induce relative rotation between the bolt head and the remainder of the bolt assembly. This relative rotation serves to disengage the interrupted screw segments 182 and 184 whereby the bolt assembly may continue to move toward the rear of the breech housing even after the recoil energy of the gun barrel has been absorbed by the buffer springs 100, 118 and 122. In the event that the gun jams with the bolt head locked in its forward position, a pull on the rear portion 154 of the bolt will cause the cam segments 162 on the bolt head to cooperate with the cam slots 164 in the bolt head cam so as to rotate the bolt head 156 out of locking.

engagement with the breech ring 82 so as to permit hand cocking of the gun.

As the bolt head 156 moves from the shell firing position towards the rear, the ejector cam 202 cams the ejector 180 into shell ejecting position. The ejected shells leave the breech housing 50 through the bottom opening 199.

Movement of the bolt assembly 150 operates the cam tube drive bushing 204 which is slidably mounted within the cam tube 206 which in turn is rotatably mounted within the cover 54. A bearing stud 205 carried by the cover 54 supports the front end of the tube 206 as shown in Fig. 5. The cam tube drive bushing 204 is provided with a downwardly projecting portion 208 which is in engagement with an aperture in the lug 209 on the bolt 150 and is operated thereby. The projection 208 also cooperates with a spiral cam slot 210 provided in the wall of the cam tube 206 whereby upon reciprocation of the bolt 150, the cam tube 206 is caused to rotate.

One section of the outer wall of the cam tube 206 is provided with external gear teeth at 212 which mesh with teeth 214 provided on the belt feed slide element 216. By virtue of the above described arrangement, reciprocation of the bolt assembly 150 causes rotation of the cam tube 212 which in turn operates the belt feed slide element 216, in a manner explained more fully in my co-pending application S. N. 536,229 to which reference is hereby made for a detailed description of the belt feed mechanism.

A coil spring 217 biases the cam tube drive bushing 204 together with the bolt 154 into the forward position thereof. A hand cocking arrangement is provided which comprises a flexible cable 220 provided with a hand engaging element 224 on the one end thereof and an element 226 on the other end thereof for engaging the cam tube drive bushing 204. The ends of the element 226 project through the slots 227 in the tube 229 which is disposed between the springs 217 and 228. The coil spring 228 biases the element 226 into its forward position at all times. In order to hold the bolt assembly 150 in any desired position, a cable clutch or friction brake generally designated by the reference numeral 230 has been provided which comprises a plurality of clutch jaws 232 for gripping and holding the cable 220 in any desired position. A compression spring 234 normally holds the jaws 232 out of cable gripping position. In order to move the jaws into cable gripping position it is necessary to push forward on the cable guide bell 240. Forward movement of the bell 240 overcomes the force of the spring 234 and causes the jaws 232 to be cammed into cable gripping position by the beveled surface 231 on the clutch housing 233. The jaws 232 remain in the cable gripping position until the cable 220 is pulled outwardly at which time the jaws momentarily move with the cable until the cam surfaces no longer force the jaws in gripping engagement with the cable.

In order to remove the belt feed slide assembly 65 from the housing 252 it is necessary to remove the mechanism within the cam tube 206. This mechanism may be removed by lifting the cover 54 and depressing the locking plunger 302 so as to make it possible to slide out the mechanism from within the cam tube 206. This mechanism being removed, the cam tube is free to rotate whereby the slide assembly 216 may be removed from the housing 252 through the end slot 253 (Fig. 1).

The slot 210 provided in the cam tube may be

arranged for feeding the shells into the receiver from the right-hand side or it may be arranged to feed the shells into the receiver from the left-hand side. When it is desired to change over from right-hand shell feeding to left-hand shell feeding it is necessary to change the cam tube so as to change over from a cam tube having a right-hand helical slot to a cam tube having a left-hand helical slot. It is also necessary to remove the housing 252 and reverse it end for end so as to move the belt feeding and holding pawls from the one side of the gun to the other side of the gun.

It will be noted that the cover 54 is a sheet metal stamping formed to enclose the cam tube 206 as well as other vital parts of the gun as shown. By virtue of the shape of the cover which comprises both flat and rounded portions, the cover is inherently strong, yet lightweight and inexpensive to manufacture.

While the form of embodiment of the invention as herein disclosed constitutes a preferred form, it is to be understood that other forms might be adopted, as may come within the scope of the claims which follow.

What is claimed is as follows:

1. In combination, a gun barrel, a receiver, a breech bolt slidably supported by said receiver, a guide tube having a slot in the wall thereof, a spring tube drive element disposed within said guide tube and having a portion projecting through said slot for engagement by said breech bolt, a spring within said spring tube urging said bolt forward, manual means extending into said guide tube for engaging said element to move the breech bolt into gun cocking position, and means for holding said manual means in a partial gun cocking position, said manual means comprising a flexible cable and said holding means comprising means for gripping the cable so as to hold the cable in any position desired.

2. In combination, a gun barrel, a receiver, a breech bolt slidably supported by said receiver, a guide tube having a slot in the wall thereof, a spring tube drive element disposed within said guide tube and having a portion projecting through said slot for engagement by said breech bolt, a spring within said spring tube urging said bolt forward, manual means extending into said guide tube for engaging said element to move the breech bolt into gun cocking position, and clutch means for holding said manual means in a partial gun cocking position, said manual means comprising a flexible element extending into said guide tube and projecting through one end of said guide tube, said clutch means comprising means for engaging said flexible element so as to hold said flexible element in any desired position.

3. In a machine gun comprising a casing and

mechanism within said casing for automatically effecting feeding, loading, firing and ejection in rapid repetitive succession which mechanism includes a longitudinally reciprocable breech bolt, the combination with said mechanism of a hand operated cocking cable for hand cocking said breech bolt, spring means for biasing said cable out of cocking position, clutch means for engaging said cable for holding the same in any desired position, spring means for biasing said clutch means out of cable clutching position, and manual means for positively moving said clutch means into cable clutching position.

4. In combination, a gun barrel, a receiver, a breech bolt slidably supported by said receiver, a guide tube having a slot in the wall thereof, a spring tube drive element disposed within said guide tube and having a portion projecting through said slot for engagement by said breech bolt, a spring within said spring tube urging said bolt forward, a guide bell supported at the rear end of said guide tube, manual means extending into said guide tube for engaging said element to move the breech bolt into gun cocking position, and clutch means for holding said manual means in a partial gun cocking position, said manual means comprising a flexible element extending through said guide bell and into said guide tube, said clutch means comprising means for engaging said flexible element so as to hold said flexible element in any desired position, said guide bell being arranged relative said clutch means so that a forward push on said guide bell causes said clutch means to grip said flexible element.

FRANCIS I. RATAICZAK.
